FIXED BY-PASS CONDENSER

Application filed May 11, 1928. Serial No. 277,606.

This invention relates to radio frequency amplifying circuits, and the principal object thereof is to provide a simple, novel, and efficient fixed by-pass condenser particularly adapted for use in tuned radio frequency circuits which condenser will be inexpensive to manufacture and highly efficient in operation; also to provide a novel hook-up for such circuits utilizing my fixed by-pass condensers in such a way as to effect an electrostatic balance across the filaments of the radio tubes, each fixed condenser having at the center of this electrostatic balance a conductor having its own dielectric, and each condenser being connected in such a way that the "A" power current will flow through the condenser until said electrostatic balance is reached.

Another object of the invention is to obviate some well known defects in connection with such radio tubes and their circuits, since no tuned radio frequency amplifier will be efficient unless it can be balanced against oscillations and its regeneration controlled. My novel fixed condensers form a means for balancing such circuits or systems; or for neutralizing same; and when used in an R. F. amplifier circuit acts as a balancing device, and also allows a certain amount of regeneration to take place but controlled by a variable resistor in the positive "B" battery plate lead. A small amount of regeneration is very desirable in an R. F. amplifier circuit, but not desirable in an audio system; and my condensers can be used to stop this regeneration in an audio system.

Other minor objects of the invention will be hereinafter set forth.

I will explain the invention with reference to the accompanying drawings which illustrate one practical embodiment thereof to enable others familiar with the art to adopt and use the same, and I will summarize in the claims the novel features of construction and novel combination of parts for which protection is desired.

In said drawings:—

Fig. 1 is a diagrammatic view showing the wiring diagram for a five-tube tuned radio frequency amplifying circuit, also showing therein the hook-up for eight fixed by-pass

condensers for obtaining most efficient results.

Fig. 2 shows the same circuit as in Fig. 1 but equipped with four of my novel by-pass condensers to accomplish the same results.

Fig. 3 shows diagrammatically the hook-up for one of my condensers with respect to a tube socket, R. F. coil, and "A" and "B" batteries.

Fig. 4 is a perspective view of my novel fixed by-pass condenser, detached.

Fig. 5 is an enlarged transverse section through the condenser shown in Fig. 4.

In Fig. 1 the hook up for a five-tube tuned radio frequency amplifying circuit is shown, said circuit employing two stages of radio frequency amplification and the detector circuit, also two stages of audio frequency amplification and an output transformer. The antenna 1 is connected to ground 2 through primary coil 3 of the tuning transformer 4. Secondary winding 5 is tuned by a variable condenser 6 to the frequency of the signals.

The first stage of radio frequency amplification includes tube 7 having a filament electrode 8, grid electrode 9, and plate electrode 10. The input circuit of tube 7 across the grid 9 and filament 8 is connected with the tuned circuit 5 and 6. The output circuit of tube 7 includes primary winding 11 of the radio frequency coupling transformer 12 one end 80 of said winding 11 being connected to a source of "B" battery potential (about 70 volts).

The secondary winding 13 of transformer 12 is tuned by variable condenser 14, and connects to the input circuit of electron tube 15 forming the second stage of radio frequency amplification. The output circuit of tube 15 includes primary winding 16 of coupling transformer 17 and a source of "B" battery potential (about 70 volts). The secondary 18 is tuned by variable condenser 19 and connects through grid leak and grid condenser 20 with the input circuit of detector tube 21.

The output of detector tube 21 includes primary winding 22 of the audio transformer 23 and a source of "B" battery potential (about 22½ volts). The secondary 24 of audio transformer 23 is connected in input circuit of tube 25, the output circuit of such tube in-

cluding the primary coil 26 of audio transformer 27 and a source of "B" battery potential (about 90 volts).

The secondary 28 of audio transformer 27 is connected in the input circuit of the last tube 29 which input circuit also includes a "C" battery 30. The output circuit of tube 29 includes the primary coil 31 of an output transformer 32 and a source of "B" battery potential (about 180 volts). The secondary 33 of output transformer 32 is connected across the responsive device 34 which may be a loud speaker.

The filaments of all the tubes 7, 15, 21, 25 and 29 are heated in the usual manner from an "A" battery.

I have found that unusual good results in radio reception are obtained by hooking in eight fixed by-pass condensers 40 in the above circuit, one such condenser being shunted across the filament of each of the tubes 7, 15, 25 and 29 respectively, said condensers 40 each being of small capacity usually 1.0 mfd., and producing an electrostatic balance across the filaments of their respective tubes.

One of the remaining four fixed by-pass condensers 40 in Fig. 1, is shunted across the negative "A" battery wire leading from the negative filament 8 of the tube 7 and the positive "B" battery connection of primary coil 11. Another condenser 40 is similarly shunted across the negative "A" battery wire leading from the filament of tube 15 and the positive "B" battery connection of primary coil 16. Another fixed by-pass condenser 40 is shunted across the negative "A" battery wire leading from the filament of tube 25 and the "B" battery connection of primary coil 22; and the last fixed by-pass condenser 40 is similarly shunted across the negative "A" battery wire leading from the filament of tube 29 and the positive "B" battery connection of primary coil 26.

In Fig. 2, the same tuned radio frequency circuit is shown as in Fig. 1, but the eight fixed by-pass condensers have been replaced by four of my novel three-electrode condensers 41 for accomplishing the same result. One condenser 41 has its two outer plates shunted across the filament 8 of tube 7 the central fixed plate of condenser 41 being connected with the "B" battery wire leading to primary coil 11, said condensers 41 producing the same results as the two condensers 40 for tube 7 in Fig. 1. A second condenser 41 is similarly connected in the circuit of tube 15. A third condenser 41 has its two outer plates shunted across the filament of tube 25 and its central plate connected to the "B" battery wire leading to primary coil 22; and the fourth condenser 41 is similarly connected in the circuit of tube 29. My four condensers 41 therefore in Fig. 2, replace the eight condensers 40 in Fig. 1.

In the arrangement shown in Fig. 2, in-

stead of by-passing the high frequency currents of the plate circuit back to its own tube filament in the audio system the high frequency currents are by-passed on to the next tube's filament, which I have discovered is a very good means for stopping regeneration in the audio system.

In Fig. 3 the hookup for a single fixed by-pass condenser 41, tube socket 42, R. F. coil 43, and "A" and "B" power sources respectively is shown, the current from the source of "A" power passing through the condenser until an electro-static balance is reached.

As shown in Figs. 4 and 5, the fixed by-pass condensers 41 diagrammatically illustrated in Figs. 2 and 3; preferably comprises a casing 41^a of rectangular shape, having one end open and the other closed, said casing 41^a having offset feet 41^b extending from the side in order that the casing which houses the condenser parts may be conveniently mounted above a panel board in such manner that there will be as little as possible condenser action between the panel and condenser.

Within the casing 41^a is a copper plate 41^c, having a projection 41^d extending out of the open end of the casing; said plate being coated with a hard rubber dielectric composition 41^e thoroughly insulating the copper plate 41^c, the same being capable of withstanding voltages up to about 300 volts.

Around the dielectric 41^e within the casing are wrapped two super-imposed conductors 41^f and 41^g each comprising strips of tin-foil inserted between paper dielectric strips 41^h, said conductors 41^f and 41^g being super-imposed and then together wrapped spirally around the plate 41^c in order that the plate will be disposed centrally of the wrapped conductors. By the above construction the conductors 41^f and 41^g will be insulated from each other and from copper plate.

At the outer ends of each of the wrapped tin-foil conductors 41^f and 41^g are copper wires 41^k and 41^m which extend entirely through the casing from the open end, adjacent the portion 41^d, through spaced perforations in the closed end of casing 41^a, said wires 41^k and 41^m being suitably insulated from the casing, by means of sealing wax or the like.

Between the wrapped conductors 41^f and 41^g and the casing 41^a is an insulating sheet 41^p preferably wrapped around the wound condensers to retain the same in fixed position. The open end of the casing 41^a is preferably closed, after assembly of the condenser, with sealing wax or the like, the members 41^d, 41^f and 41^m projecting therethrough.

In use, my condensers are connected in the circuit as shown in Fig. 3, with the conductors 41^f and 41^g respectively shunted across the filament of the radio tube, and the copper plate 41^c connected to the positive wire leading from the "B" battery to the primary 130

winding of the related transformer, thereby establishing an electrostatic balance across the filament of the tube, and the current from the "A" battery in Fig. 3 passing through the condenser.

5 I do not limit my invention to the exact form shown in the drawing for obviously changes may be made therein within the scope of the claims.

10 I claim:—

1. A fixed by-pass condenser comprising a plate of conducting material; a dielectric around said plate; a pair of superimposed conductors each interposed between dielectric strips and wrapped spirally around the copper plate; and electric leads for the spirally wrapped conductors and the plates.

15 2. A fixed by-pass condenser comprising a casing; a plate of conducting material in said casing having one end projecting therefrom; a dielectric around said plate; a pair of superimposed conductors each interposed between dielectric strips and wrapped spirally around the copper plate within the casing; and lead wires for the spirally wrapped conductors insulated from the casing, the plate, and from each other.

20 3. In a condenser as set forth in claim 2, perforated feet offset from one side of the casing for attaching same spaced from a support.

25 4. A fixed by-pass condenser comprising a casing; a copper plate in said casing having one end projecting therefrom; a dielectric around said plate; a pair of superimposed tin-foil conductors each interposed between paper dielectric strips and wrapped spirally around the copper plate within the casing; and lead wires for the tin-foil conductors

30 40 extending through the casing and insulated from the casing and from the copper plate and from each other.

45 5. In a condenser as set forth in claim 4, perforated feet offset from one side of the casing for attaching same to and above a support.

50 6. A double voltage by-pass condenser comprising insulated and superimposed spirally wrapped condenser conductors adapted to receive an impressed voltage; and an insulated condenser plate at the center of the spirally wrapped conductors adapted to receive a second impressed voltage.
